UNITED STATES PATENT OFFICE

2,218,944

REFRIGERATING APPARATUS

Edward R. Wolfert, Springfield, Mass., assignor to
 Westinghouse Electric & Manufacturing Company, East Pittsburgh, Pa., a corporation of Pennsylvania

Application November 5, 1937, Serial No. 172,881

17 Claims. (Cl. 62—4)

My invention relates to refrigerating apparatus and has for an object to provide improved apparatus of this kind.

Another object of the invention is to provide an improved refrigerating system of the compression type which may be operated without unloading during the starting operation.

A further object of the invention is to prevent the starting of a refrigerant compressor during periods when the pressure difference between the gas inlet and the outlet thereof exceeds a predetermined value.

A still further object of the invention is to provide an improved protective device for a refrigerant compressor wherein operation of the latter is terminated in response to an excessive head pressure and to a relatively low section pressure, and wherein starting of the compressor is prevented when the difference between the head and suction pressures exceeds a predetermined value.

These and other objects are effected by my invention as will be apparent from the following description and claims taken in accordance with the accompanying drawing, forming a part of this application, in which:

The single figure of the drawing is a diagrammatic view of a refrigerating system controlled in accordance with my invention.

Reference will now be had to the drawing, wherein I have shown a refrigerating system including an evaporator 10 for abstracting heat from the media to be refrigerated, a compressor 11 and a condenser 12, the latter being cooled in any suitable manner such as, for example, by water. The compressor 11 may be directly driven by an electric motor 13 and is preferably of the enclosed type; the motor 13 being enclosed by a casing 14 secured to the compressor 11.

Refrigerant vaporized at relatively low pressure in the evaporator 10 is withdrawn through a conduit 15 by the compressor 11 and is compressed to a relatively high pressure and delivered to the condenser 12 through a conduit 16. The compressed vapor is cooled by a water cooled coil 17 and is condensed. The cooling water enters the coil at 18 and is discharged at 19. A valve 20 may be disposed in the water circuit for controlling the flow of cooling water and may be controlled in any well known manner. Preferably, the flow of cooling water is controlled in accordance with head or condensing pressure.

Condenser refrigerant is conveyed from the

condenser 12 to the evaporator 10 through a conduit 21 having a suitable expansion device 22 connected therein for reducing the pressure of the refrigerant to the value at which it is vaporized. Preferably, the device 22 is a conventional thermostatic expansion valve and controls the flow of refrigerant to the evaporator 10 in response to a predetermined value of the superheat in the vapor discharged from the evaporator 10. From the foregoing description, it will be apparent that the system operates in the well known compressor-condenser-expander cycle so that no further description of the operation is deemed necessary.

The refrigerating system disclosed may be employed for cooling any medium, but the evaporator which I have disclosed is employed for cooling a gas such as air and is provided with fins 23 for increasing its heat transfer surface. A fan 24 may be used for effecting forced circulation of the air over the evaporator 10.

Protection against excessive head pressure and abnormally low evaporating pressure during operation is provided by a device diagrammatically shown at 25, which also functions in accordance with my invention, to prevent starting of the motor 13 at times when the pressure differential between the high and low pressure sides of the system exceeds a predetermined value. Starting of the motor and compressor is, therefore, effected only when the load is at or below a predetermined value. Accordingly, the system may be operated without an unloader and without providing a driving motor having a capacity greater than that necessary for running. A description of the control device 25 will now be given.

The device 25 includes a normally closed switch 26, that is actuated by either of a pair of pressure responsive bellows 27 and 28. The bellows 27 is connected by a tube 29 to the pressure conduit 16 defining a portion of the high side of the system and the bellows 28 is connected by a tube 31 to the low side of the system and preferably to the suction conduit 15. The switch 26 may include a pivoted arm 32 connected by a snap acting spring 33 to a pivoted switch arm 34, the latter carrying a movable contact 35 that engages a stationary contact 36 in the closed position of the switch. A stop 37 limits movement of the switch arm 34 in opening direction. The main pivoted arm 32 is biased in switch closing direction by a spring 38 and a stop 39 is provided for limiting movement of the arm 32 in this direction.

Movement of the main arm 32 upwardly and downwardly effects opening and closing of the switch 26 in a snap acting manner as the spring 33 passes the pivot of the switch arm 34. Upward movement of the main pivoted arm 32 is effected by a rod 41 connected to a bell crank 42 that is actuated by the bellows 28. A lost motion connection is provided between the rod 41 and lever 32 and may include a projection 43 on the lever 32 disposed within a slot 44 in the rod 41. Normally or during periods when the evaporator pressure is above a predetermined value the rod 41 may move upwardly and downwardly without actuating the switch 26 but when the pressure is depressed to an abnormally low value, the rod 41 is raised sufficiently to cause the projection 43 to be engaged and lifted by the rod 41, whereby the switch 26 is opened.

Operation of the switch 26 is also effected by the high side bellows 27. A second rod 45 includes a slot 46 within which a second projection 47 on the lever 32 is disposed. The rod 45 is connected to a bell crank 48 that is actuated by the bellows 27. Normally the switch 26 is unaffected by movement of the bellows 27 due to the lost motion provided by the connection between the projection 47 and slot 46. However, when the head pressure increases to abnormally high value the projection 47 is engaged by the rod 45 and the switch is moved to its open position. As described hereinafter, opening of the switch 26 due to abnormally high head pressure or low evaporator pressure stops operation of the compressor. Adjustment of the pressures at which the bellows 27 and 28 operate the switch 26 may be provided by adjustable springs 51 and 52 which oppose movement of their respective bellows.

A second switch 53 is provided in the device 25 and is actuated conjointly by the bellows 27 and 28 and which is closed only when the difference in pressures between the high and low sides is below a predetermined value. The switch includes relatively movable contacts 54 and 55, the first of which moves with movement of the bellows 27 and the second of which is actuated by the bellows 28. The contact 54 is carried by a support 56 that may be secured to the bell crank 48 and movable therewith. The contact 55 is carried by a spring 57 forming a part of the pivoted lever 58 that is actuated by the bellows 28 and bell crank 42. One end 59 of the lever 58 is held in engagement with the bell crank 42 by means of a spring 61 that biases the lever 58 in 55 clockwise direction.

The various elements that actuate the contacts 54 and 55 are so proportioned that the contacts are separated when the pressure differential between the high and low sides of the system exceeds a predetermined value, such as for example, 50 lbs. When the differential is depressed to 50 lbs., due to contraction of the bellows 27 or expansion of the bellows 28 or both, the contacts 54 and 55 engage. Of course, when the pressure differential is below 50 lbs. the contacts 54 and 55 are engaged; the contact carrying spring 57 being deflected due to the depressed position of the contact 54. As described hereinafter, the motor 13 may be started only when the contacts 70 54 and 55 of the switch 53 are engaged.

The switches 26 and 53 are connected in series in a control circuit including a conductor 63 energized from a suitable power source represented by line conductors L-1 and L-2. Preferably the 75 conductors L-1 and L-2 define a power source

of relatively low potential. The conductor 63 is connected to the operating coil 64 of a relay 65, the latter including a main switch 66 and a control switch 67 that is connected in parallel with the switch 53 by a conductor 68. Energization 5 of the coil 64 effects closing of the switches 66 and 67, and, conversely, deenergization of the same effects opening of the switches 66 and 67. The switch 68 is connected in the motor circuit 71 that is energized from a suitable source of 10 relatively high potential power represented by the terminals T-3 and T-4.

Starting and stopping of the compressor motor 13 may be effected by a master switch 72 15 preferably thermostatically operated and connected in the control conductor 63. When thermostatically actuated, the switch 72 may be operated in response to the temperature of the media being refrigerated or to the temperature of the evaporator 10 in a manner well understood 20 in the art. In the present embodiment it will be assumed that the master switch 72 is closed and opened in response to predetermined high and low temperature of the air being refrigerated. Having described the various elements which 25 may be employed in practising the invention, I will now describe the operation thereof.

Operation

As shown in the drawing, the master switch 30 72 is open, so that the compressor and motor 13 are inactive. The switch 26 is closed as the head pressure and the evaporator pressure are respectively below and above the values at which this switch 26 is opened. The switch 53 is closed 35 which indicates that the pressure differential between the high and low sides of the system is below 50 lbs. Accordingly, the system is in condition for operation when called upon by the master switch 72. 40

When the temperature of the air being treated and circulated by the fan 24 has increased to predetermined value, the thermostatically operated master switch 72 is closed and thereby energizes the control circuit including the line conductor L-1, the switch 72, the conductor 63, the engaged contacts 35 and 36 of the normally closed switch 26, the closed contacts 54 and 55 of the switch 53, the operating coil 64 of the relay 65 and line conductor L-2. Accordingly, the 50 switches 66 and 67 of the relay 65 are closed, the former energizing the main circuit including terminal T-3, switch 66, conductor 71, the motor 13 and the terminal T-4. Operation of the compressor 11 and its driving motor 13 is therefore initiated. Closing of the switch 67 energizes the conductor 68 which defines a shunt across the switch 53 for a purpose to be described hereinafter. 55

Operation of the compressor 11 depresses the 60 pressure and temperature of the refrigerant in the low side of the system including the evaporator 23 and the suction conduit 15. The pressure in the high side of the system is raised, which high side includes the pressure conduit 16, 65 condenser 12 and the liquid supply conduit 21. Evaporation of refrigerant is effected in the evaporator 23 under control of the thermostatically operated expansion valve 22 so that the air translated by the fan 24 is depressed in temperature. 70

The increase in the head pressure expands the bellows 27 in opposition to the bias of the spring 51 and moves the contact 54 upwardly in a direction away from the contact 55. Likewise, 75

the reduction in pressure on the low side of the system contracts the bellows 28 so that the bell crank 42 is moved counter-clockwise and the lever 58 is moved clockwise by the bias of the spring 61. The contact is therefore moved downwardly and away from contact 54. Opening of the switch 53 does not affect deenergizing of the control circuit as the latter is maintained closed by the switch 67. Operation of the compressor 11 continues until the temperature of the media being cooled has been depressed to a predetermined value at which time the master switch 72 is opened for deenergizing the control circuit. Accordingly, the relay 65 opens its main switch 66 and control switch 67 so that operation of the compressor 11 and its driving motor 13 are terminated.

During the inactive period of the compressor 11 the evaporator pressure rises and the head pressure or condensing pressure is depressed. Accordingly, the contacts 54 and 55 are moved in closing direction and, when the pressure differential between the high and low sides has been depressed to 50 lbs. the contacts 54 and 55 are engaged for conditioning the system for the starting operation.

Starting of the compressor is prevented if the thermostat 72 closes during an inactive period of the compressor and before the pressure differential between the high and low sides of the system has decreased to 50#, due to the fact that the switch 53 is maintained open by the high pressure differential. In this event, the relay remains deenergized and its switches 66 and 67 remain open so that the compressor motor 13 is not energized by the closing of the thermostat 72. Starting of the compressor 11 is effected when the pressure differential is depressed to 50# at which time the switch 53 closes and energizes the relay 65. Accordingly, the switches 66 and 67 are closed and the motor 13 is energized for driving the compressor as described heretofore.

The foregoing description of the operation of the system relates to a normal cycle of operation wherein the switch 26 remained closed due to the fact that the condensing pressure did not exceed the pressure at which the bellows 27 effects opening of the switch 26 and the evaporating pressure remained above the low value at which the bellows 28 opens the switch 26. The lost motion connections defined by the slots 46 and 44 and their associated projections 47 and 43 prevent operation of the switch 26 during a normal cycle as described heretofore.

If the head pressure increases to an abnormally high value during operation, the amplitudes of the bellows 27 is sufficient to open the switch 26 and, therefore, terminate operation of the motor 13. This terminating operation of the motor 13 is also effected by the opening of the switch 26 if the evaporator pressure is decreased to a predetermined low value. When the head pressure decreases and the evaporator pressure increases to normal value, the switch 26 is automatically closed by the spring 38.

As the differential in pressure between the high and low sides of the system must be below a predetermined value during starting, the system may be operated without an unloading device and without providing a motor having a capacity substantially above the capacity necessary for running operation. In systems operated without an unloader, it has heretofore been the practice to provide a larger and more expensive motor

than is necessary for running operation in order to initiate operation of the compressor.

From the foregoing, it will be apparent that I have provided an improved refrigerating system which may be operated without an unloading device and without providing a motor having a capacity substantially above that necessary for running operation. Furthermore, protection is afforded against the high head pressure and low suction pressure.

The protection device 25 which I have disclosed is diagrammatically shown for the sake of clearness and certain refinements usually found in control instruments of this character have been omitted. Preferably, the protection device 25 is constructed as a unit and employs the same pressure responsive elements for actuating both switch structures 26 and 53. I have shown the switch 26 actuated by both bellows 27 and 28 but it will be understood that these pressure responsive elements may operate switching means other than that shown at 26.

While I have shown my invention in but one form, it will be obvious to those skilled in the art that it is not so limited but is susceptible of various changes and modifications without departing from the spirit thereof, and I desire, therefore, that only such limitations shall be placed thereupon as are imposed by the prior art or as are specifically set forth in the appended claims.

What I claim is:

1. Refrigerating apparatus comprising a high pressure and a low pressure side, means for circulating refrigerant through the high and low pressure sides and means responsive to a predetermined high differential in pressure between the high and low pressure sides for rendering said circulating means incapable of being started, said differential pressure responsive means being ineffective to control the circulating means during active periods thereof.

2. Refrigerating apparatus comprising an evaporator, a condenser, means for circulating refrigerant through the evaporator and condenser, a motor for driving the circulating means and means responsive to a predetermined high difference in pressure between the condenser and evaporator for rendering the motor incapable of being started, said last-mentioned means being ineffective to terminate operation of the motor during operating periods thereof.

3. Refrigerating apparatus comprising a condenser and evaporator defining portions of the high and low pressure sides of the apparatus respectively, a compressor for translating refrigerant through the high and low pressure sides, a motor for driving the compressor, a switch for controlling energization of the motor, means responsive to a predetermined high difference in pressure between the high and low pressure sides of the apparatus for opening said switch and a second switch connected in parallel with the first switch and opened and closed in response to the deenergization and the energization of the motor respectively.

4. Refrigerating apparatus comprising a condenser and evaporator defining portions of the high and low pressure sides of the apparatus respectively, a compressor for translating refrigerant through the high and low pressure sides, a motor for driving the compressor, a switch adapted to prevent energization of the motor while it is deenergized, means operable in response to a predetermined maximum difference

between the pressures in said high and low-pressure sides to render said switch effective to prevent energization of said motor, and means for rendering said switch ineffective to terminate energization of the motor while the latter is energized.

5. Refrigerating apparatus comprising a high pressure side and a low pressure side, means for translating refrigerant through the high and low pressure sides, means responsive to predetermined high and low pressures in the high and low sides, respectively, for rendering the refrigerant translating means inactive and means effective during inactive periods of the translating means and responsive to a predetermined high difference in pressure between the high and low sides for preventing the starting of the translating means.

6. Refrigerating apparatus comprising high and low pressure sides, means for translating refrigerant through the high and low pressure sides, electrical means for actuating the refrigerant translating means, means responsive to predetermined high and low pressure in the high and low sides, respectively, for deenergizing the electrical means and means responsive to a predetermined high difference in pressure between the high and low pressure sides for preventing energization of the electrical means during inactive periods thereof.

7. In refrigerating apparatus, the combination of refrigerant evaporating means, means for withdrawing refrigerant vaporized in the evaporating means, electrical means for actuating the refrigerant withdrawing means, means for condensing the withdrawn vaporous refrigerant, means for conveying the condensed refrigerant to the evaporating means, a master switch for controlling the energization of the electrical means, means responsive to a predetermined high pressure of the condensed refrigerant for rendering the electrical means inactive, means responsive to a predetermined low pressure of the evaporated refrigerant for rendering the electrical means inactive and means responsive to a predetermined high differential in pressure between the condensed and evaporated refrigerant for preventing energization of the electrical means during its inactive periods.

50. 8. Refrigerating apparatus comprising high and low pressure sides, a compressor for translating refrigerant through the high and low pressure sides, a motor for driving said compressor, switching means for controlling energization of the motor, means responsive to predetermined high and low pressures of the high and low sides, respectively, for opening the switching means, a second switch controlling energization of the motor, means responsive to a predetermined high difference in pressure between the high and low sides for opening said second switch, and means effective during operating periods of the motor for rendering said second switch incapable of controlling energization of the motor.

65. 9. In refrigerating apparatus, the combination of an evaporator, a compressor for compressing refrigerant vaporized in the evaporator at relatively low pressure, a condenser for liquefying the compressed refrigerant at relatively high pressure, a motor for driving the compressor, switching means for controlling energization of the motor and opened in response to predetermined high and low pressures of the compressed and vaporized refrigerant, respectively, a switch connected in series with said switching means

and opened in response to a predetermined high difference in pressure between the compressed and vaporized refrigerant, and means for shunting said switch during periods when the motor is energized.

10. In refrigerating apparatus, the combination of an evaporator, a compressor for compressing refrigerant vaporized in the evaporator at relatively low pressure, a condenser for liquefying the compressed refrigerant at relatively high pressure, a motor for driving the compressor, a switch for controlling energization of the motor and opened in response to predetermined high and low pressures of the compressed and vaporized refrigerant, respectively, a second switch connected in series with said first mentioned switch and opened in response to a predetermined high difference in pressure between the compressed and vaporized refrigerant, and a third switch connected in parallel with the second switch and closed during periods when the motor is energized.

11. In refrigerating apparatus, the combination of an evaporator, a compressor for compressing refrigerant vaporized in the evaporator at relatively low pressure, a condenser for liquefying the compressed refrigerant at relatively high pressure, a motor for driving the compressor, first and second pressure responsive elements responding, respectively, to the pressures of the compressed and vaporized refrigerant, switching means for controlling energization of the motor and actuated by either of said first and second elements to its open position in response to predetermined high and low pressures of the compressed and vaporized refrigerant, respectively, a second switch connected in series with said switching means and actuated conjointly by the pressure responsive elements to its open position in response to a predetermined high difference in pressure between the compressed and vaporized refrigerant and a third switch connected in parallel with the second switch and opened and closed during periods when the motor is deenergized and energized, respectively.

12. Refrigerating apparatus comprising an evaporator, a compressor for withdrawing relatively low pressure vapor from the evaporator and for compressing the same to a relatively high pressure, a condenser for liquefying the high pressure vapor, a motor for driving the compressor, a normally closed switch for controlling energization of the motor, an element responsive to the pressure of the compressed refrigerant and connected to said switch for opening the same in response to a predetermined high pressure of the compressed refrigerant, a second element responsive to the pressure of the low pressure vapor and connected to said switch for opening the same in response to a predetermined low pressure of the low pressure vapor, a second switch connected in series with the first switch, and actuated conjointly by both of said pressure responsive elements, said second switch being open when the difference in pressures between the high and low pressure vapor exceeds a predetermined value, and a third switch connected in parallel with the second switch and opened and closed in response to deenergization and energization of the motor respectively.

13. In refrigerating apparatus or the like, the combination of a motor compressor unit including a compressor for translating fluid from a region of low pressure to a region of high pressure and an electric motor for driving the compressor.

5 a first switch for normally controlling energization of the motor, a second switch adapted to prevent energization of the motor independently of the action of the first switch, means responsive to a high difference between the pressures in said high and low pressure regions for controlling said second switch to prevent energization of the motor, and means for rendering said second switch ineffective to control energization of the motor 10 while the unit is in operation.

14. In a refrigerating apparatus or the like, the combination of a motor compressor unit including a compressor for translating fluid from a region of low pressure to a region of high pressure 15 and an electric motor for driving the compressor, first means for normally controlling the starting and stopping of the motor compressor unit, and second means operable in response to a predetermined maximum difference between the pressures in said high and low pressure regions to 20 prevent starting of the unit, independently of the action of said first means, but permitting starting in response to a lower difference in said pressures and permitting the unit to continue to operate, once it is started, to provide a pressure difference greater than said predetermined maximum pressure difference.

15. The method of controlling the operation of a motor compressor unit including a compressor operable to translate fluid from a region of low pressure to a region of high pressure and an electric motor for driving the compressor, which method comprises normally controlling energization of the motor in response to a load condition 30 of the unit but delaying starting of the unit, when the unit is idle and the difference between the pressures in said high and low pressure regions is high, until said difference is reduced to 35

a predetermined low value, continuing operation of the motor compressor unit, once it is started, independently of increase in said pressure difference above said predetermined low value, and terminating operation of the unit in response to 5 said load condition.

16. In refrigerating apparatus or the like, the combination of a motor compressor unit including a compressor for translating fluid from a region of low pressure to a region of high pressure 10 and an electric motor for driving the compressor, and means operable in response to a predetermined maximum difference between the pressures in said high and low-pressure regions to prevent starting of the unit but permitting 15 starting in response to a lower difference in said pressures and permitting the unit to continue to operate, once it is started, to provide a pressure difference greater than said predetermined 20 maximum pressure difference.

17. In refrigerating apparatus or the like, the combination of a motor compressor unit including a compressor for translating fluid from a region of low pressure to a region of high pressure and an electric motor for driving the compressor, first and second elements responsive to the pressures in said high and low-pressure regions, respectively, means controlled by one of said pressure-responsive elements and arranged 25 to prevent operation of the unit when the pressure imposed on the associated pressure-responsive element reaches a predetermined value, and means actuated conjointly by both of said pressure-responsive elements for effecting a control 30 of the operation of the unit in response to the 35 difference between the pressures imposed on said pressure-responsive elements.

EDWARD R. WOLFERT.
